UNITED STATES PATENT OFFICE.

JOSEPH GERMAIN WOLFF, OF PARIS, FRANCE.

ARTICLE OF FURNITURE.

SPECIFICATION forming part of Letters Patent No. 335,667, dated February 9, 1886.

Application filed August 11, 1885. Serial No. 174,094. (No model.) Patented in France June 25, 1885, No. 169,783; in Belgium July 10, 1885, No. 69,551, and in England July 14, 1885, No. 8,512.

To all whom it may concern:

Be it known that I, JOSEPH GERMAIN WOLFF, gentleman, a citizen of the Republic of France, residing at Paris, have invented a new and Improved Article of Furniture, (for which I have obtained Letters Patent in France, dated June 25, 1885, No. 169,783, for fifteen years; Belgium, dated July 10, 1885, No. 69,551, for fifteen years, and England, dated July 14, 1885, No. 8,512, for fourteen years;) and I do hereby declare that the following is a full and exact description thereof, reference being made to the accompanying drawings.

15 According to this invention a number of traveling cases or trunks are constructed in a peculiar manner, so that they may be placed together, one above another, forming an article of furniture containing a writing-desk, 20 drawers, cases, looking-glasses or mirrors, shelves, &c. When the article of furniture is taken to pieces, each of the trunks composing it can be used or carried about separately.

25 In the illustrative drawings hereunto annexed, Figure 1 shows a perspective front elevation of the article of furniture put together complete, and Fig. 2 shows a similar elevation with the trunks composing the same 30 opened.

The article of furniture is formed of a series of traveling cases or trunks, *a b c d e*, which, when stripped of their traveling-covers fit one over the other, the bottoms and tops 35 of each being provided for that purpose with alternating interlocking projections and recesses *x x'*, which fit into one another, as shown. A cornice, *k*, which completes the article of furniture, is movable, and can be 40 folded at the joints *k' k*, to enable it to be inclosed in one of the trunks. The lowermost trunk, *a*, rests on two cross-pieces, *ff'*, which act as feet. It is divided vertically by a partition, *g*, into two parts, one of which is 45 closed hermetically by a face-board, *h*, and a door, *h'*. In the compartment thus formed soiled linen or other objects can be placed.

The trunk *b*, next above, comprises a range 50 of drawers, *t*, and below them a sliding writing-desk, *m*, which may be drawn out and pushed in by the handles *m' m'*. It is supported by the movable bar *m''*, which can be drawn forward. The shelf or desk *m* may be

arranged to let down, instead of sliding horizontally, if preferred. Any number of looking-glasses or mirrors *n n* and shelves *rr* may be arranged and fitted according to the requirements of the owner. These shelves or divisions *rr*, which divide the trunks into two parts, may be hinged so as to lift up, to facilitate the storage of valuables. All the trunks open in front by two doors, *p p'*, secured by locks or bolts. The trunks, with or without panels, are furnished with handles *q q* at the ends. They are also furnished with upright rods *s s*, forming supports for the front of the article of furniture, and with angle-pieces *v v*, placed at the internal corners, in order to give the necessary strength and rigidity. Metal frames may be used instead of the angle-pieces *v v*, if preferred.

It may be observed, first, that each of the trunks can be fitted with strapped cases for linen or clothing, and may be closed, when the doors *p p'* are open, by curtains or by 75 boards, so that the said trunks shall present all the advantages of ordinary trunks furnished with strapped cases, toilet-boxes, hat-boxes, &c.; secondly, that any one of the trunks can be suppressed or be placed the first, second, third, fourth, or fifth, &c., in order, and that articles of furniture thus formed may serve for cases or boxes of various kinds, book-cases, &c.

The number, shape, and dimensions of the 85 trunks may be varied according to circumstances and the purpose which the article of furniture they compose is intended to fulfil.

I do not claim a box having pivoted pins, nor anything shown in Patent No. 85,811, 90 granted to E. Gill, January 12, 1869.

Having now particularly described and ascertained the nature of the said invention and in what manner the same is to be performed, I declare that what I claim is—

The combination of the series of trunks *a b c d* with one another, said trunks having the interlocking contact-faces *x x'*, the folding front doors, *p p'*, and upright rods *s*, so as to be adapted to constitute a single article of furniture, substantially as herein shown and described.

JOSEPH GERMAIN WOLFF.
